(57) **CLAIM**

The ornamental design for legs for a piano, as shown and described.

DESCRIPTION

FIG. 1 is a perspective view of the top, front and left side of legs for a piano according to a first embodiment showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a perspective view of the top, front and left side of legs for a piano according to a second embodiment;

FIG. 9 is a top plan view thereof;

FIG. 10 is a front elevational view thereof;

FIG. 11 is a right side elevational view thereof;

FIG. 12 is a left side elevational view thereof;

FIG. 13 is a rear elevational view thereof; and,

FIG. 14 is a bottom plan view thereof.

The portions of the piano in broken lines are shown for illustrative purposes only and form no part of the claimed design.
